UNITED STATES PATENT OFFICE.

OSCAR N. WIMBERLY, OF JACKSONVILLE, FLORIDA.

POCKET SAFETY DEVICE.

Application filed February 19, 1921. Serial No. 446,403.

To all whom it may concern:

Be it known that I, OSCAR N. WIMBERLY, a citizen of the United States, residing at Jacksonville, in the county of Duval and 5 State of Florida, have invented certain new and useful Improvements in Pocket Safety Devices; and I do hereby declare the following to be a full, clear, and exact description of the invention, such as will enable others 10 skilled in the art to which it appertains to make and use the same.

The invention provides means to prevent the loss of a purse or like pocket receptacle either by theft or displacement since positive securing means are resorted to and fastened to the purse or like article and to the 15 pocket of the apparel.

In accordance with the invention a fastener containing member is secured within 20 the pocket and a complemental member is attached to the purse or like article to be made secure against loss.

When the purse is in the pocket the complemental fastening means are engaged 25 thereby preventing surreptitious removal or casual displacement of the purse.

Other objects and advantages will be apparent and suggest themselves as the nature of the invention is understood.

30 While the drawings illustrate an embodiment of the invention, it is to be understood that in adapting the same to meet different conditions and requirements, various changes in the form, proportion and minor 35 details of construction may be resorted to without departing from the nature of the invention.

Referring to the accompanying drawings forming a part of the specification,

40 Figure 1 is a detail view of a pocket illustrating an application of the invention,

Figure 2 is a sectional detail,

Figure 3 is a detail view of the purse having one member of the safety means applied 45 thereto,

Figure 4 is a detail view of the member adapted to be secured to the pocket, and

Figure 5 is a detail view of the member adapted to be applied to the purse or like 50 part.

Figure 6 is a sectional view on the line 6—6 of Figure 4, with the member carried by the purse in position within the pocket carried member.

55 Corresponding and like parts are referred to in the following description and design-

nated in the several views of the drawings by like reference characters.

The safety means include complemental members 1 and 2. Each of these members 60 preferably consists of a flexible strip. The member 1 is adapted to be secured within a pocket 3. The member 2 is adapted to be attached to an edge portion of the purse 4 or like part. The members are made secure by any suitable fastening means. The member 1 is preferably made secure at both ends, whereas the member 2 is made secure 65 at one end only.

A rod or like part 5 is mounted upon the member 1 so as to receive a rotary movement. 70 A finger 6 projects laterally from the rod or part 5 and constitutes a locking element. A finger piece 7 is disposed at one end of the rod 5 for manipulation thereof. A spring 8 associated with the rod 5 normally holds the locking finger or element 6 in operative position. The spring 8 and finger piece 7 are preferably disposed at opposite ends of the rod 5. The locking finger 6 is 75 preferably located intermediate the ends of the rod 5. The finger piece 7 is elongated and has a lug 7^a preferably disposed at a right angle to the locking finger 6 so as to engage the rear side of plate 1 to constitute a stop to 80 normally hold the locking finger in operative position.

For convenience, the member 2 is located 85 at an edge portion of the purse 4 or like part. A slot 9 is formed lengthwise of the part 2 and is adapted to receive the locking finger 6. The slot 9 accommodates the locking finger 6 so that the purse or like part may occupy a relative position in the pocket so as to touch the bottom thereof.

The member 2 is adapted to slip into a pocket or space provided in the member 1. The locking finger 6 is adapted to extend through the slot 9 and through an opening formed in a side of the member 1. When placing the purse or like article in the pocket or removing it therefrom, the finger piece 7 is turned to bring the locking finger 6 in the plane of the member 1 so that the member 2 may be slipped into or withdrawn 100 from the pocket or space of the member 1 105 as will be readily understood.

What is claimed is:

1. Safety meant of the character specified, comprising complemental members, a 110 rod rotatably mounted upon one of the members and provided with a laterally ex-

tending locking finger, and an elongated finger piece secured to the rod and having a lug disposed approximately in a plane at a right angle to the locking finger and engaging the member to hold the locking finger in locking position.

2. Safety means of the character specified, comprising complementary members, a rod rotatably mounted upon one of the members and provided with a laterally extending locking finger, an elongated finger piece secured to the rod and having a lug disposed in a plane at a right angle to the locking finger, and a spring coacting with the rod and lug to normally hold the locking finger in operative position.

3. Safety means of the character specified, comprising a pocketed member adapted to be secured to the wearing apparel, a rod 20 rotatably mounted upon the member and provided with a lateral locking finger, a spring in cooperative relation with the rod for normally holding the locking finger in operative position, a finger piece having a lug forming a stop for the rod, and a complementary member adapted to be attached at one end only to the purse or like part and adapted to fit into the pocket of the first mentioned member and to be engaged by the 30 said locking finger.

4. Safety means of the character specified, comprising a pocketed member, a rotatable rod mounted on the member at one side of the pocket and provided intermediate of 35 its ends with a laterally extending locking finger, a spring at one end of the rod normally holding the locking finger in operative position, an elongated finger piece secured to the opposite end of the rod and 40 having a lug disposed in a plane at a right

angle to the plane of the locking finger, and a slotted member adapted to be introduced into the pocket of the first mentioned member.

5. A device of the class described comprising a pair of complementary members of which one is adapted to be received within the other, the first member carrying a rotatable rod provided with a locking finger, and a finger piece provided with a stop lug, and means normally urging said stop lug into a position to hold said locking finger in locking position.

6. A device of the class described comprising a pair of complementary members of which one is adapted to receive the other, the first member carrying a rotatable rod provided with a locking finger and a finger piece provided with a stop lug, and means 55 yieldingly holding said stop lug into a position to hold said locking finger in locking position.

7. A device of the class described comprising a plate carrying a pocket, a pair of ears carried by said plate and disposed at 60 opposite sides of said pocket, a rotatable rod carried by said plate, a locking finger carried by said rod, a finger piece provided with a stop lug carried by said rod at one end thereof, a spring coiled about said rod and 65 abutting at one end against one of said ears, and said spring coacting with said stop lug to hold said locking finger in normal position.

In testimony whereof I affix my signature 70 in presence of two witnesses.

OSCAR N. WIMBERLY.
